UNITED STATES PATENT OFFICE.

MARTIN DEILLER, OF NEWARK, NEW JERSEY.

TOBACCO-STRIPPER.

No. 813,868.

Specification of Letters Patent.

Patented Feb. 27, 1906.

Application filed July 25, 1904. Serial No. 217,921.

To all whom it may concern:

Be it known that I, MARTIN DEILLER, a citizen of France, residing at Newark, in the county of Essex and State of New Jersey, have invented certain new and useful Improvements in Tobacco-Strippers; and I do hereby declare the following to be a full, clear, and exact description of the invention, such as will enable others skilled in the art to 5 which it appertains to make and use the same, reference being had to the accompanying drawings, and to numerals of reference marked thereon, which form a part of this specification.

15 This invention relates to certain improvements in that class of tobacco-stripping machines shown in my prior patent, No. 716,627, issued December 23, 1902, the objects of the present invention being to secure a more compact machine, to enable a cylinder or drum to be employed instead of a flat table, to thus combine the booking device with the table, to provide an improved registering attachment, to secure suitable intermittent action 20 of the different parts, and to obtain other advantages and results, some of which may be referred to hereinafter in connection with the description of the working parts.

25 The invention consists in the improved tobacco-stripping machine and in the arrangements and combinations of parts of the same, all substantially as will be hereinafter set forth, and finally embraced in the clauses of the claim.

30 Referring to the accompanying drawings, in which like numerals of reference indicate corresponding parts in each of the several figures, Figure 1 is a plan of my improved machine. Fig. 2 is a side elevation of the same.

35 Fig. 3 is an elevation of the machine from the front end. Fig. 4 is a vertical longitudinal section taken upon line x , Fig. 8, looking in the direction indicated by the single arrow; and Fig. 5 is a similar view of a portion of the 40 machine looking in the opposite direction as indicated by the double arrow on line x' , Fig. 8. Figs. 6 and 7 show in edge view and plan, respectively, certain leaf-holding fingers hereinafter described. Fig. 8 is a transverse vertical section of the machine upon line x' , Fig.

45 5. Fig. 9 is a side view of the forward part of the machine, showing the registering attachment in detail; and Fig. 10 illustrates another position of the parts of said registering apparatus. Fig. 11 shows the registering apparatus in edge view. Fig. 12 is a

50 plan of a certain sliding trip or catch. Fig. 13 is a section of the same upon line y , Fig. 12. Figs. 14 and 15 are detail views of the rotary cutter in side elevation and edge view 55 and illustrating a slightly-modified construction; and Figs. 16 and 17 are sectional views of said cutter, taken on lines z and z' , respectively, of Fig. 14, looking in the directions indicated by the arrows.

55 In said drawings, 2-2 indicate the side frames or plates of my improved machine, which are vertically arranged parallel to each other at a suitable distance apart to receive between themselves the working parts of the 60 machine, which will be hereinafter described. Between said plates extends a main or drum shaft 3, upon which is mounted a drum or cylinder 4, comprising longitudinal sections 5, each having circular end pieces 6 and a 65 curved peripheral portion 7. At the inner adjacent ends of the sections each is provided with a flange 8, projecting radially beyond the outer surface of the drum-section, said flanges being at their edges beveled each toward its drum-section to present sharp cutting edges 9. Around the said drum or cylinder 4 are arranged belts 10 to hold the leaves in place upon said drum-sections, each drum-section preferably having three of these 70 belts. Each belt is carried around the under surface of the drum, as at 11, Fig. 2, over an upper pulley 12 at the front of the cylinder 4 and then downward at a distance from said cylinder over rollers 12 13 beneath the cylinder 14 15, the latter roller 15 being adjacent to the cylinder 4 at the upper part of its rear portion. The 75 belts are thus doubled around the drum, the inner fold lying against the lower part of the 80 same and the outer fold being carried upon pulleys and held taut by means of the pulley 13, being journaled upon one end of the bell-crank lever 16, having a weight 17 at the 85 other end and at its bend a fulcrum pin 18, confined in a slot 19 of a fixed arm 20, projecting from the frame of the machine. Thus as the leaves are put into the machine, 90 one at each revolution of the drum, they are held by said belts and become superposed 95 one upon the other to form a book, the weight 17 being lifted as the book thickens. Each belt, it will be understood, is independent of the others, and the number or width of the 100 belts may be varied at pleasure.

105 Each leaf is inserted with its tip first, as shown in Fig. 1, the mid-rib of the leaf being

between the flanges 8 of the two drum-sections. Thus as the leaf is drawn inward by the revolution of the drum each half lies upon one of the drum-sections 5 and the rib is cut out by a cutter 21, coöperating with the sharp edges 9 of the flanges 8. Said cutter is stationed at the front of the machine or forward side of the cylinder 4 and comprises a series of curved blades 22, (see Figs. 4, 14, 17,) projecting radially from a hub 23, mounted upon a transverse shaft 24, journaled in the side frames 2 parallel to the main or drum shaft 3 and adapted to be rotated by means hereinafter described. Said blades are each formed by an arm or body portion 25, wedge-shaped in cross-section, the thicker part being at the forward or curved edge of the blade and having upon the opposite sides of said body portion knives 26 26, which thus diverge forwardly and project beyond the body part of the arm. Moreover, a portion of the arm near the hub and which first enters the slot between the flanges 8 8, is narrower or thinner than the part farther out from the hub, whereby the entrance of each blade between the flanges is facilitated and a shearing action insured. The leaf-rib thus cut out passes inwardly between the drum-sections 5 5 and is directed downward and outward by a guide 27, projecting into the said space from a point below the cylinder. A series of rotating arms 28 are also provided to enter said slot between the drum-sections and aid in dislodging the leaf ribs or stems therefrom so that they fall to the floor.

The drum-sections 5 5 are preferably one fast on the shaft 3 and the other slideable and held toward the first by means of a spring 29 on said shaft between the drum and side frame. Tie-rods 30, of any suitable type, are of course provided to hold the side frames in rigid relation.

At the upper part of the front of the machine just back of the roller 12 for the belts 45 10 is arranged, between the side frames 2 2 of the machine, a transverse shaft 31, having at its central portion an arm 32, which extends toward the drum 4 and is bifurcated at its end. Each arm or bifurcation of said 50 arm 32 carries a guide-strip 33, adapted to lie against the leaf adjacent to the flange 8 of the drum and hold the said leaf down against said drum. Said strips 33 are preferably connected by rollers 34, extending across the flanges 8 and cutting edges 9 of the drum, and the forward ends of said guide-strips are curved upwardly, as at 35, to facilitate the insertion of the leaves. These guide-strips serve to hold the ribs of each leaf against the 55 cutting edges 9 9 of the drum as the leaf enters the machine, and resiliency of such holding is secured by a spring 36, attached at one end to the said frame 2 of the machine and at the other end to a fixed arm 37 of the shaft 31.

65 It is necessary while the leaves are in the

machine that they be positively clamped at some point to prevent shifting or displacement, and to accomplish this end I have provided fingers 38 on opposite sides of the drum-slot, which are adapted to grasp the tips of the leaves and press them firmly against the drum. I furthermore secure an automatic raising of said fingers as the drum comes into position to receive a new leaf, so that insertion of said leaf is not impeded, it being understood that the drum pauses momentarily for such insertion of the leaf and that as soon as rotation again commences the fingers 38 close upon the leaf. To this end each drum-section has arranged upon its shaft 3, inside the drum and adjacent to the cutting end thereof, an arm 39, which projects upward to or nearly to the peripheral wall of the drum-section and provides thereat a slideway 40 for the stem 41 of the clamping-finger 38, said stem protruding through the surface of the drum and the finger being extended forwardly and curved to fit the drum-surface. Said stem 41 is held retracted, preferably, by means of a spiral spring 42, engaging a stop 43 at the end of the stem and at its other end abutting against the slideway 40. Upon one side of said slideway, as at 44, is fulcrumed a bent lever 45, one arm of which, as 46, engages the stem 41 of the said finger and the other arm 47 of which is adapted as the drum rotates to engage a fixed pin 48 upon a suitable support 481 from the side frame 2. Said pin 48 is so arranged that it will be engaged by the said bent lever just before the drum comes in position to receive a new leaf, the said bent lever being operated to raise the fingers 38 and hold them raised while the drum comes to a stop, as hereinafter described. The fresh leaf is then inserted, and as the drum starts up again the lever 45 is freed from the pin 48 and the fingers grip the leaves. It will be understood that there are two of these leaf-holding fingers 38, one on either side of the slot between the drum-sections, and that the same may be of any desired shape, although, preferably, quite broad, as shown in Figs. 6 and 7. By the construction described it will be noted that a movement of the said holding-fingers in a direction exactly perpendicular to the surface of the drum is secured.

On one end of the main or drum shaft 3 outside the side frame of the machine is fixed a sprocket 49, and at the lower part of the machine is a transverse driving-shaft 50, journaled in the side frames and carrying a driving-sprocket 51, from which a chain 52 transmits motion to the drum-shaft sprocket 49, above mentioned. Said shaft 50 is driven by a belt-pulley 501 or in any other suitable manner, and the said sprocket-wheel 51, which carries the chain to the drum-shaft 3, is preferably adapted to be connected to or disconnected from said shaft 50 by clutch means 130

next to be described. Said sprocket 51 is normally loose upon the shaft 50 and at its side next the machine is provided with an annular series of teeth 53, adapted to be engaged by pawls 54, rotating with the shaft. Said pawls are each pivoted in radial position with respect to the shaft upon a supporting-spider 55 and at their ends next the shaft are connected, as by links 56, (see Fig. 11,) to a sleeve 57, slideable on the shaft. A spiral spring 58, coiled upon the shaft, serves to normally force said sleeve away from the spider 55 and hold the pawls 54 in clutched relation to the sprocket 51. Said sleeve 57 is moved to release the pawls 54 by means of a lever 59, (see Fig. 3,) fulcrumed on the side frame 2, as at 60, and having its upper forked end engaging the said sleeve to slide the same upon the shaft 50. From the lower arm of said lever 59 a link or rod 61 extends to the lower arm of a bell-crank lever 62, pivoted upon the frame of the machine beneath the same, and being normally held by a spring 63 with the sleeve 57 away from the pawls. A controlling-lever 64, also pivoted upon the frame of the machine, is adapted to engage the other arm of the said bell-crank lever 62 and swing the same against the power of its spring 63, said controlling-lever having at its end away from the said bell-crank lever a rod 65, which extends upward and is connected to a latch 66, (see Fig. 9,) adapted to be tripped by a pin 67 upon a disk 671 on the drum-shaft 3 at each revolution thereof. Said pin is stationed at a point such that the said latch 66 will be tripped and the clutch thrown out of engagement to stop the rotation of the drum when it is in exactly the right position to receive a fresh leaf. As soon as the leaf has been inserted the latch 66 is released from the pin 67, as hereinafter described, and the clutch therefore thrown in again to rotate the drum.

Preferably a treadle 68, convenient to the operator's foot, is connected by a link 69 with the bell-crank lever 62 from beneath, so that said operator can at any moment throw the clutch and stop the drum.

The latch 66 is made in two sections 70 71, the section 70 being fulcrumed upon a stud 72 and providing ways for the other section 71 to slide longitudinally upon said first-mentioned section 70. Ears 73 74 project from the sections, between which ears is arranged a spiral spring 75, normally holding the sections in extended relation. A rod 76, passing through the ear 73 on the fixed section 70 and through the spring 75, is secured to the ear 74 of the slideable section, and this rod has a turned or hooked outer end adapted to be slidably engaged by an arm 77 of a transverse shaft 78 of the machine, said shaft having another arm 79, from which a connecting-rod 80, extending to a second treadle 81, preferably mounted on the same shaft 82

with the first-mentioned treadle 68. By this second treadle 81 and its connections the operator releases the latch 66 after a new tobacco-leaf has been fed onto the drum to again throw in the clutch at the driving- 70 sprocket 51 and start the drum rotating.

To enable the number of leaves stripped and booked upon my improved machine to be registered, I apply to the latch 66 the following registering means: The stud 72 upon which said latch is pivoted has also pivoted thereon concentric with said latch and outside the same a disk 83 and at the inner side thereof a smaller ratchet-wheel 84. Spring-pressed pawls 85 are carried by the latch 66 80 to engage said ratchet-wheel, and thus as the latch is swung by engagement with the pin 67 of the disk 671 the ratchet-wheel 84 and disk 83 are turned. Any suitable means (not shown) may be applied to said disk for recording the oscillations of the lever, and preferably a pin 86 is carried by said disk to engage and trip a hammer 87, adapted to strike a gong 88 at the end of a given number of revolutions of the drum and warn the operator 90 that a book is complete.

Obviously a registration upon any revolution of the drum may be avoided, if desired, by retracting the latch 66 from the path of the pin 67.

For driving the rotary cutter 21 I have shown upon the drum-shaft 3 a gear 89, intermeshing with a smaller gear 90 upon the cutter-shaft, and for rotating the stem-clearing arms 28 the shaft 91, upon which 100 said arms are mounted, is connected by a sprocket-chain 92 with the driving-shaft 50. Obviously, however, any other suitable driving means might be employed.

A forward portion of the frame, in which 105 the cutter 21, guide-strips 33, and belt-rollers 12 and 121 are journaled, is hinged, as at 93, so that it may be tipped away to permit access to the drum, as shown in outline in Fig. 2. A hinged shield or guard 94 is also 110 provided at the rear of the machine to cover the belt-pulley 15 and close in the interior mechanism.

Having thus described the invention, what I claim as new is—

1. The combination with a drum presenting a circumferential slot with cutting edges on opposite sides thereof, and means for holding tobacco-leaves thereon, of a rotary cutter having a series of radial arms adapted to turn in said slot, each arm comprising a body portion flaring both from the hub radially outward and from its rear edge toward the forward edge, and knife-blades mounted on the sides of said body portion.

2. The combination with the circumferentially-slotted drum, and means for holding tobacco-leaves thereon, of a rotary cutter having a series of radial arms adapted to enter the slot of the drum, each arm compris- 130

- ing a body portion wedge-shaped in cross-section, with its widest edge forward, and knife-blades mounted on the sides of said body portion.
- 5 3. In a tobacco - stripping machine, the combination with a rotary drum, circumferentially slotted to receive the mid-rib of a leaf, and means for rotating said drum, of curved pressure-strips adapted to lie against the drum on opposite sides of said slot, and means for resiliently supporting said pressure-strips.
- 15 4. In a tobacco - stripping machine, the combination with a rotary drum, circumferentially slotted to receive the mid-rib of a leaf, and means for rotating said drum, of curved pressure-strips adapted to lie against the drum on opposite sides of said slot, rollers mounted upon said strips and lying between the same and across the drum - slot, and means for resiliently supporting said pressure-strips.
- 25 5. In a tobacco - stripping machine, the combination with a rotary drum, circumferentially slotted to receive the mid-rib of a leaf, and means for rotating said drum, of a resiliently-supported arm extending toward the drum in the plane of its slot and being bifurcated adjacent to said slot, a curved pressure-strip upon each bifurcation of said arm, adapted to lie against the drum at one side of its slot and having its forward end curved outward, and rollers mounted between and upon said pressure - strips and extending across the slot of the drum.
- 35 6. In a tobacco - stripping machine, the combination with a drum and means for imparting to said drum an intermittent rotary motion, of leaf-holding fingers normally lying against the surface of the drum, supporting means permitting said fingers to move away from the drum but always retaining their parallel relation thereto, and tripping means adapted to raise said fingers just before the
- drum stops in its rotary movement and release them just as the drum starts again.
7. The combination with the drum adapted to receive tobacco-leaves, of an arm fixed on the shaft of said drum and providing a radial slideway, a stem arranged in said slideway, and projecting through the drum-surface, a clamping-finger upon said stem outside the drum and parallel to the surface thereof, a spring normally forcing said stem toward the drum-shaft, and tripping means adapted to raise said fingers away from the drum at predetermined intervals.
8. In a tobacco-stripper, a frame, a shaft, a drum on said shaft and means for turning the same; an arm on the shaft providing a radial slideway, a stem in said slideway, a clamping-finger upon said stem outside the drum, a spring normally forcing said stem toward the shaft, a bent lever fulcrumed upon the drum and adapted at one end to engage said stem, and a pin upon the frame adapted to be engaged by the other end of said lever.
9. In a tobacco-stripper, a frame, a shaft, a drum on said shaft and means for turning the same, an arm on the shaft providing at one side of its outer end a tubular slideway having a slot in its side, a stem in said slideway having a lateral pin lying in said slot, a clamping member upon said stem outside the drum-surface, a stop upon the inner extremity of the stem, a coiled spring upon said stem between the slideway and said stop and adapted to force the stem inward toward the shaft, and tripping means upon the drum adapted to engage said pin of the stem.
- In testimony that I claim the foregoing I have hereunto set my hand, this 12th day of July, 1904.

MARTIN DEILLER.

Witnesses:
